UNITED STATES PATENT OFFICE.

MATHEW HILGERT, OF NEW YORK, N. Y.

SHOE.

1,039,396.

Specification of Letters Patent. Patented Sept. 24, 1912.

Application filed June 15, 1912. Serial No. 703,881.

To all whom it may concern:

Be it known that I, MATHEW HILGERT, a citizen of the United States, and resident of the borough of Manhattan, city, county, and State of New York, have invented certain Improvements in Shoes, of which the following description, in connection with the accompanying drawings, is a specification, like reference characters on the drawings indicating like parts in the several figures.

This invention relates to boots and shoes and more particularly to improvements in boots and shoes such as are worn by persons having certain distortions or malformations of the feet.

It frequently happens that a shoe of standard form does not fit the foot of the wearer properly and the arches of the foot are thrown out of normal position and the foot is given thereby a tendency to "roll" toward one side or the other which if not corrected results in a badly unbalanced muscular condition of the foot. Many expedients have been adopted in the construction of shoes for the purpose of correcting this condition but so far as known to me the resulting shoes are more or less distorted and are unsatisfactory because their conspicuousness calls attention to the wearer's defective foot. Also the disarrangement of the lines of the shoe such as the throat and the lace opening and the side seams connecting the vamp and quarters, the symmetrical location of which lines has become established by experience as affording greatest comfort and most pleasing appearance, which has characterized earlier constructions has been objectionable.

The present invention aims to provide a boot or shoe which will correct such tendencies of the foot to "roll" by building up the foot supporting portion of the shoe upon one side and thereby reducing the abnormal strain upon the ligaments of the foot, while at the same time maintaining the normal relations of the lines of the upper to the wearer's foot. This is accomplished by providing a filler or false insole of any suitable material such as felt, leather or the like, having one edge of greater average thickness than the opposite edge throughout its length, such thickness varying to conform to the bottom of the foot, and in order to allow for the increased thickness of the filler on that side of the shoe where the thickness

occurs the vamp of the upper is cut with an excess of upper material on the side adjacent to the thicker portion of the filler to compensate approximately for such greater thickness. This prevents distortion of the upper with relation to the last during the lasting of the shoe over the filler and preserves the normal relations of the lacing opening and side seams to the foot whereby comfort and inconspicuous appearance of the shoe is maintained.

A shoe constructed in accordance with this invention will tend to restore to normal balance the entire muscular organization of a foot, and this is accomplished without altering the appearance of the exterior of the shoe or disturbing the proper relation of the different parts of the shoe to the foot of the wearer.

The invention will now be described in connection with the drawings, which show a shoe embodying a preferred construction in accordance with the invention, and will then be more particularly pointed out in the claims.

Figure 1 is a view in cross section looking toward the toe showing the filler and an insole of a welt shoe with the upper in lasted position; Fig. 2 is a view in perspective, and partly in section, of the fore-part of a shoe made in accordance with the present invention; Fig. 3 is a view in cross section of a completed shoe showing the displaced position of the foot in the shoe and by contrasting lines the relative locations of the lacing opening to the foot in this position in a shoe embodying this invention and a shoe made without the invention; Fig. 4 is a perspective partly in cross section of the filler.

The preferred method of making the shoe constituting the present invention is disclosed and fully described in my copending application Serial No. 660,886, filed November 17, 1911.

In the drawings 2 represents a last shaped to conform to the foot and 4 a false insole or filler of leather, or the like of such form as to lift one side of the last 2 a sufficient height to counteract the tendency to "roll" of the particular foot for which the last was made. As is shown in Fig. 4, this filler is made of varying thickness to conform to the foot upon that side of the shoe where it is desired to raise the foot and is applied to the last before the shoe is lasted.

so that the shoe having been shaped to the last with the filler thereon will fit the foot of the wearer for which the last was made as more fully described in the above mentioned 5 co-pending application. The customary insole 6 is placed upon the false insole 4 and the shoe lasted in the usual manner.

As clearly shown in Fig. 3, the foot is supported with its bottom substantially in a 10 plane, indicated by the line *a*—*a*, at an angle to a plane parallel with the tread face of the outer sole 8, as indicated by line *b*—*b*. By the use of this filler the foot is displaced in the shoe so that, in a shoe not 15 embodying this invention, the lacing opening and side seams would be distorted relatively to their normal position on the foot of the wearer, such displacement being approximately as indicated by dotted lines, 20 Fig. 3. In accordance with this invention the vamp is cut unsymmetrically, or with an excess of stock on that side which is adjacent to the thicker portion of the filler to compensate for the displaced position of 25 the foot in the shoe and thereby allow the lacing opening and side seams to assume their symmetrical position on the foot. In Fig. 3 the approximate position of the throat of the shoe on the foot when no excess vamp 30 material is allowed for the displaced position of the foot, is indicated at (c) and the stock between that position and the correct position of the throat on the foot as indicated at (d) is substantially the excess 35 amount of vamp material which is required to compensate appropriately for the excess thickness of the filler, whereby the lines of the upper are made to assume their correct positions on the foot. The welt 2 is sewed 40 to the upper 10 and insole 6 by stitches 14, a filling 16 being added and the outersole 8 attached by the stitches 18 to the welt 12 in the usual manner.

Having explained the nature of this invention I claim as new and desire to secure by Letters Patent of the United States:

1. A shoe having a filler inserted within the shoe, said filler being thicker on one side than on the other, and having an excess of vamp material adjacent to the thicker portions of the filler sufficient to compensate approximately for the excess of thickness in the filler and thereby adjust the lines of the upper with relation to the wearer's foot in the position given to it by the filler.

2. A shoe having a filler inserted above the innersole, which filler is of greater average thickness upon one side of the shoe than upon the other, and having an excess of vamp material on the side of the shoe adjacent to the thicker edge of the filler to compensate substantially for the displacement of the foot of the wearer from normal relation to the tread face of the outsole and thereby insure normal relations of the lines of the upper to the foot of the wearer.

3. In a welted boot or shoe the combination with the upper, outersole and innersole, of a filler thicker on one side than on the other throughout its length to support the wearer's foot at an angle to the tread surface of the outersole transversely of the shoe, said upper being formed with an excess of upper material adjacent to said thicker edge of the filler to compensate approximately for such greater thickness and thereby provide for the proper relation of the lacing opening and side seams of the shoe relatively to the foot of the wearer.

In testimony whereof I have signed my name to this specification in the presence of two subscribing witnesses.

MATHEW HILGERT.
